US00D848465S

(12) United States Design Patent (10) Patent No.: US D848,465 S
Smith et al. (45) Date of Patent: * May 14, 2019

(54) DISPLAY SCREEN OR PORTION THEREOF WITH A GRAPHICAL USER INTERFACE

(71) Applicant: JPMorgan Chase Bank, N.A., New York, NY (US)

(72) Inventors: Amanda Smith, Brooklyn, NY (US); Amanda Valladares, Brooklyn, NY (US); Erika Scott, Brooklyn, NY (US); Melora Zaner, New York, NY (US); Christina Noonan, Jersey City, NJ (US); Sarah Bradford, San Diego, CA (US); Karmen Kaufmann, New York, NY (US); Kaoru Kumatani, Brooklyn, NY (US); Rodrigo Miguel, Brooklyn, NY (US); Jules Toulemonde, Munich (DE)

(73) Assignee: JPMorgan Chase Bank, N.A., New York, NY (US)

() Term: 15 Years

(21) Appl. No.: 29/622,922

(22) Filed: Oct. 20, 2017

Related U.S. Application Data

(63) Continuation of application No. 29/613,546, filed on Aug. 10, 2017.

(51) LOC (11) Cl. 14-04

(52) U.S. Cl.

USPC D14/486

(57) CLAIM

The ornamental design for a display screen or portion thereof with a graphical user interface, as shown and described.

DESCRIPTION

The FIGURE depicts a front view of a display screen or portion thereof with a graphical user interface showing our design.

The broken line showing a display screen with graphical user interface is included for the purpose of showing portions of the article which form no part of the claim.

1 Claim, 1 Drawing Sheet
